MEASUREMENT OF PIEZOELECTRIC CRYSTAL CHARACTERISTICS

David I. Kosowsky, West Newton, Mass., assignor to Research Corporation, New York, N.Y., a corporation of New York

Filed Apr. 13, 1956, Ser. No. 578,124

1 Claim. (Cl. 29—155.5)

This invention relates to piezoelectric crystals for wave filters, and more specifically it relates to the measurement of certain characteristics of crystals which significantly affect the properties of such filters.

In addition to their use as frequency control elements for oscillators, piezoelectric crystals have also been used as circuit elements in wave filters, particularly wave filters of the band-pass type for which they are most ideally suited. Although, in general, the band-pass characteristics of a filter employing crystals, that is a crystal filter, will be superior to an equivalent filter which employs only capacitive and inductive elements, there has not been as wide a use of crystal filters as would ordinarily be expected under these circumstances. One of the main reasons for this is that hitherto the adjustment of the crystals to conform certain of their characteristics to predetermined values as called for in the filter design has involved such as a large amount of labor that the cost of each filter became excessive. Also conventional measuring techniques whereby these characteristic values of the crystals are established have not been sufficiently accurate in general to permit predetermined filter specifications to be met within reasonable tolerance limits. In many cases this has led to a trial and error process of selection of crystals for use in a particular filter design which is especially costly where only a relatively few units of like design are to be manufactured.

It is an object of this invention, therefore, to provide a technique for measuring characteristics of piezoelectric crystals which permits such characteristic values as are important in the realization of a particular crystal filter design to be established quickly and accurately.

As a concomitant to the foregoing, it is a further object of the invention to obviate much of the empirical practice generally associated with the manufacture of crystal filters to predetermined specifications.

The novel features of the invention, together with further objects and advantages thereof, will become more readily apparent from the following detailed description of the invention wherein reference will be had to the accompanying drawings.

In the drawings:

Fig. 1 is a schematic diagram of an equivalent circuit to represent a first piezoelectric crystal;

Fig. 2 is a graph illustrating the impedance characteristic of the crystal of Fig. 1;

Fig. 3 is a schematic diagram of an equivalent circuit to represent a second piezoelectric crystal;

Fig. 4 is a graph illustrating the impedance characteristic of the crystal of Fig. 3;

Fig. 5 is a schematic diagram of a crystal filter of lattice type configuration incorporating the crystal of Fig. 1 in each series arm and the crystal of Fig. 3 in each shunt arm;

Fig. 6 is a graph illustrating the attenuation characteristic of the filter of Fig. 5;

Fig. 7 is a schematic diagram of an illustrative form

of measuring circuit suitable for carrying out the method of measurement according to the present invention;

Fig. 8 is a graph illustrating the voltage output characteristic of the circuit of Fig. 7 when in a first condition; and

Fig. 9 is a graph similar to that of Fig. 8 with the circuit of Fig. 7 in a somewhat different condition.

With reference first to Fig. 1 those skilled in the art will recognize that the circuit therein illustrated is 10 equivalent to a piezoelectric crystal in idealized form in that the resistive or dissipative component of impedance associated with the crystal has been omitted. Components L_1 and C_1 which are generally termed the series inductance and series capacitance, respectively, of the crystal are connected in series with one another between the terminals of the crystal 1—1, and component C_0 which is generally termed the shunt capacitance, is connected in parallel with the series combination of L_1 and C_1 . The reactance Z_a of the circuit of Fig. 1 as a function of frequency f is plotted in Fig. 2. From Fig. 2 it will be observed that the circuit has two critical frequencies, namely a zero at frequency f_a , the resonant frequency of the crystal where the reactance Z_a is zero, and a pole at frequency f_b , the antiresonant frequency of the crystal where the reactance Z_a is infinite.

Fig. 3 is an equivalent circuit of a second piezoelectric crystal similar to that of Fig. 1, the series inductance, series capacitance, and shunt capacitance, in this case being denoted by L_1' , C_1' and C_0' , respectively. A plot 30 of the reactance Z_b of this circuit, which of course also has one zero and one pole, is shown in Fig. 4, the location of the zero being denoted by the frequency f_a' and the location of the pole being denoted by the frequency f_b' .

35 Although the shunt capacitance of a crystal C_0 (or C_0') can be measured accurately enough for most filter applications, hitherto the methods employed for measuring and adjusting the series capacitance C_1 or the series inductance L_1 (for a given resonant frequency, the one determines the other) have been generally inadequate. This is particularly true as regards the most general and hence the most common type of crystal filter configuration, namely a lattice filter which incorporates at least one crystal in each series arm, such as that represented 40 by Fig. 1, and at least one crystal in each shunt arm, such as that represented by Fig. 3. A simplified form of this type of filter is illustrated in Fig. 5 where the individual crystals have been designated A and B. In a variation of this circuit two divided plate crystals (four terminals each) are utilized for the series and shunt arms respectively, instead of the four separate crystals as shown. In another variation, a hybrid equivalent circuit is used which has the same transmission characteristics as the lattice but requires only a single pair of crystals (as shown for example in the Bell System Technical Journal of October, 1937, pages 423—436). Whether or not either of these well known expedients is adopted, however, is immaterial, in principle at least, to the method 45 of the present invention.

60 In any case, what is important, in addition to the establishment of the proper resonant frequencies for the crystals, is the adjustment of the series capacitance C_1 or more particularly the ratio of the series capacitance in each lattice arm namely

$$\frac{C_1}{C_1'}$$

65 because this ratio directly affects the relative positions of the attenuation maxima of the filter. It is to the measurement and adjustment of this ratio that the present invention is primarily directed.

With reference now to Fig. 6, where the attenuation α of the filter circuit of Fig. 5 is plotted as a function of frequency f , it will be observed that two attenuation peaks occur, one at frequency $f_{\infty 1}$ and the other at frequency $f_{\infty 2}$. The pass band of the filter is defined by frequencies f_a and f_b' and within the pass band are found the frequencies f_b and f_a' all of which correspond to the zeros and poles, respectively, of Figs. 2 and 4. In Fig. 6 the separation between f_a and f_a' has been designated by Δ_0 , the separation between $f_{\infty 1}$ and f_a has been designated Δ_1 , and the separation between $f_{\infty 2}$ and f_a' has been designated Δ_2 .

Since the attenuation peaks at $f_{\infty 1}$ and $f_{\infty 2}$ occur at frequencies where the reactance Z_a of the crystal in each series arm becomes equal to the reactance Z_b of the crystal in each shunt arm, it follows that:

$$Y_a = Y_b \text{ when } f = f_{\infty 1} \text{ or } f = f_{\infty 2} \quad (1)$$

where Y_a equals $\frac{1}{Z_a}$ and Y_b equals $\frac{1}{Z_b}$.

The same is true irrespective of the relative positions of the poles and zeros of crystals A and B, and therefore, it should be understood that the attenuation characteristic illustrated by way of example in Fig. 6 bears no relation whatever to the attenuation characteristic to be realized ultimately according to the method of the present invention. Thus f_a' and f_b need not coincide and in fact will not coincide initially in the usual case. Expanding Y_a and Y_b in terms of their equivalent circuit components as denoted in Figs. 1 and 3 Equation 1 may be written

$$2\pi f C_0 - j2\pi f C_1 \frac{f_a^2}{(f_{\infty 2}^2 - f_a^2)} = 2\pi f C_0' - j2\pi f C_1' \frac{f_a'^2}{(f_{\infty 2}^2 - f_a'^2)} \quad (2)$$

where f_{∞} equals $f_{\infty 1}$ or $f_{\infty 2}$. In the case where f_{∞} equals $f_{\infty 1}$ Equation 2 becomes:

$$(C_0 - C_0') = \frac{C_1 f_a^2}{f_{\infty 2}^2 - f_a^2} - \frac{C_1' f_a'^2}{f_{\infty 2}^2 - f_a'^2} \quad (3)$$

and in the case where f_{∞} equals $f_{\infty 2}$ Equation 2 becomes:

$$(C_0 - C_0') = \frac{C_1 f_a^2}{f_{\infty 2}^2 - f_a^2} - \frac{C_1' f_a'^2}{f_{\infty 2}^2 - f_a'^2} \quad (4)$$

subtracting Equation 4 from Equation 3 and simplifying the result yields:

$$\frac{C_1}{C_1'} = \frac{f_a^2}{f_a'^2} \frac{(f_{\infty 2}^2 - f_a^2)(f_{\infty 2}^2 - f_a'^2)}{(f_{\infty 2}^2 - f_a^2)(f_{\infty 2}^2 - f_a'^2)} \quad (5)$$

An approximate form of Equation 5 may be obtained by writing:

$$\begin{aligned} f_{\infty 2}^2 &= (f_a - \Delta_1)^2 = f_a^2 - 2\Delta_1 f_a + \Delta_1^2 \\ f_{\infty 2}^2 &= (f_a + \Delta_2)^2 = f_a^2 + 2\Delta_2 f_a + \Delta_2^2 \\ f_a^2 &= (f_a + \Delta_0)^2 = f_a^2 + 2\Delta_0 f_a + \Delta_0^2 \\ f_a'^2 &= (f_a - \Delta_0)^2 = f_a'^2 - 2\Delta_0 f_a + \Delta_0^2 \end{aligned} \quad (6)$$

Substituting Equation 6 in Equation 5 yields:

$$\frac{C_1}{C_1'} = \frac{f_a^2 \Delta_1 (\Delta_2 + \Delta_0)}{f_a'^2 \Delta_2 (\Delta_1 + \Delta_0)} \left[\frac{1 - \frac{\Delta_0}{2f_a' + \Delta_2}}{1 - \frac{\Delta_0}{2f_a + \Delta_1}} \right] \quad (7)$$

If in the bracketed expressions of Equation 7 Δ_1 and Δ_2 are neglected then Equation 7 becomes:

$$\frac{C_1}{C_1'} = \frac{f_a^2}{f_a'^2} \frac{1 + \frac{\Delta_0}{\Delta_2}}{1 + \frac{\Delta_0}{\Delta_1}} \quad (8)$$

or

$$\frac{C_1}{C_1'} = \frac{f_a^2}{f_a'^2} \frac{1 + \frac{(f_a' - f_a)}{(f_{\infty 2}^2 - f_a')}}{1 + \frac{(f_a' - f_a)}{(f_a - f_{\infty 1}^2)}} \quad (8a)$$

The error involved in this approximation is negligible for all practical purposes since Δ_1 and Δ_2 will always be relatively insignificant as compared with $2f_a$ and $2f_a'$, respectively.

In Fig. 7 there is shown an illustrative form of circuit to carry out the method of measurement according to the present invention. As shown in Fig. 7, with switches 11-14 in their x positions, the crystals A and B of Figs. 1 and 3 are connected in a lattice (or bridge) configuration like that of Fig. 5, one each of the series and shunt arms being represented by the dotted lines 15 and 16, respectively, to simplify the drawing. In other words, dotted line 15 represents a crystal just like the series arm crystal 20 A and dotted line 16 represents a crystal just like the shunt arm crystal B. In practice this result follows naturally from the use of divided plate crystals or the hybrid equivalent circuit mentioned heretofore. Connected to the one end of the lattice is an input circuit including a transformer 17 with a capacitor 18 across its secondary winding and a capacitor 19 in series with its primary winding, the latter in turn being connected to a variable frequency oscillator 20. Connected to the other end of the lattice is an output circuit which includes a transformer 21 having a pair of capacitors 22 and 23 connected across its primary and secondary windings respectively. This output circuit is in turn coupled to a tuned amplifier 24 through a switch 25 and the amplifier is coupled to a vacuum tube voltmeter 26. Finally, a pair of calibrated variable capacitors 27 and 28 are connected across the crystals A and B through switches 29 and 30 respectively.

An additional circuit is provided between the oscillator 20 and the amplifier 24 whereby the individual crystals may be selectively connected directly between the oscillator and the amplifier. Thus, one of the output terminals of the oscillator is connected to the y terminals of switches 11, 13 and the other output terminal of the oscillator is connected to a common point or ground. To complete the circuit there are provided individual connections from the y terminals of switches 12 and 14 to the y terminal of switch 25, and a pair of resistors 31 and 32. Resistor 31, which is of relatively low value (1-100 ohms depending on frequency), is connected from the ungrounded terminal of oscillator 20 to ground, and resistor 32, which has a value similar to that of resistor 31, is connected from the y terminal of switch 12 to ground.

In operation, switch 25 is placed in its y position, switches 13 and 14 are placed in their x positions, and switches 11 and 12 are placed in their y positions. Under these conditions a simple measuring circuit is formed whereby the resonant frequency of crystal A may be measured or adjusted as required. To measure the frequency of crystal A, the frequency of oscillator 20 is adjusted until the indication provided by the vacuum tube voltmeter 26 is a maximum. This maximum corresponds to the resonant frequency f_a of crystal A as indicated in Fig. 8. The resonant frequency of the shunt crystal B may be similarly measured if the relative positions of switches 11 and 12, on the one hand, and switches 13 and 14 on the other be reversed. Thus, switches 11 and 12 are placed in their respective x positions, switches 13 and 14 are placed in their respective y positions, and the oscillator is once again adjusted for a maximum indication of the vacuum tube voltmeter, such maximum corresponding to the resonant frequency f_a' of crystal B.

Having determined the resonant frequencies of both the series and shunt crystals A and B which defines the value of Δ_0 (Fig. 6), switches 11-14 are each placed in

their x positions, switches 29 and 30 are closed if this has not already been done, and switch 25 is moved to its x position. Under these conditions the crystals are connected in a lattice configuration, the input end of the lattice being coupled to the oscillator 20, and the output end of the lattice being coupled to the amplifier 24 and vacuum tube voltmeter 26. Oscillator 20 is then set to a frequency which is less than the frequency f_a , and the capacitors 27 and 28 are adjusted for a minimum indication on the vacuum tube voltmeter, corresponding to an attenuation maximum. In this way, the frequency of maximum attenuation $f_{\infty 1}$ (Fig. 6) is made to coincide with the oscillator frequency and Δ_1 is caused to equal the difference between the oscillator frequency and the resonant frequency f_a . Next the oscillator frequency is increased until the other attenuation maximum or peak at $f_{\infty 2}$ is located, the frequency difference between $f_{\infty 2}$ and f_a corresponding to Δ_2 in Fig. 6. The ratio

$$\frac{C_1}{C_1'}$$

may now be determined by substituting in Equation 8 the values f_a , f_a' , Δ_0 , Δ_1 and Δ_2 as determined in the foregoing.

Thus far no mention has been made of optimum or reasonable values of Δ_0 , Δ_1 and Δ_2 . An analysis of the measurement error which may arise from inaccuracies in the oscillator frequency indications discloses that the degree of accuracy to which the ratio

$$\frac{C_1}{C_1'}$$

can be measured increases as Δ_1 increases. On the other hand, when Δ_1 is relatively large, it is difficult to distinguish the position of the attenuation peak at $f_{\infty 1}$ because of system noise. In general, a good compromise is obtained when Δ_1 is in the order of $10\Delta_0$. With respect to the frequency difference Δ_0 itself, the choice of Δ_0 will depend somewhat on the type of filter application for which the crystals are intended. If the crystals A and B are to be used in a narrow band filter then the frequencies f_a , f_a' which define Δ_0 can be the resonant frequencies called for in the filter design. If the crystals are to be employed in a wide band filter, however, their resonant frequencies will be too widely separated, and in this case two alternatives are possible.

According to one alternative, the resonant frequency of the crystal A as called for in the filter design is chosen as the frequency f_a and the crystal B is adjusted to a frequency f_a' about .1% of f_a cycles (Δ_0) above f_a . The ratio

$$\frac{C_1}{C_1'}$$

is then measured and the crystals adjusted until the measured value of

$$\frac{C_1}{C_1'}$$

is given by

$$\frac{C_1}{C_1'} = \left(\frac{C_1}{C_1'} \right)_x \frac{f_a'}{(f_a')_x} \quad (9)$$

where

$$\left(\frac{C_1}{C_1'} \right)_x$$

and $(f_a')_x$ are the values called for in the filter design. Accordingly, when the resonant frequency of crystal B is subsequently raised to its ultimate value $(f_a)_x$ by further adjustment (grinding) of crystal B, then the series capacitance C_1' , will be correspondingly decreased so that the

75 from which the shunt capacitance C_0 and series capaci-

final ratio of the series capacitances of crystals A and B will be

$$\left(\frac{C_1}{C_1'} \right)_x$$

as desired.

The second alternative for the wide band filter case is most useful where a pair of crystals have already been adjusted for use in a particular filter design, and it is a duplication of these crystals for additional filters of like design which is desired. If the crystals to be duplicated are denoted A_s and B_s, then the first step is to regrind crystal A_s until its resonant frequency f_s is increased by an amount Δ_0 , where Δ_0 is about .1% of f_a cycles. As previously described, the circuit of Fig. 7 is collaterally adapted to measure crystal resonant frequency, and hence the resonant frequency of crystal A_s may be measured and adjusted by simply substituting crystal A_s for crystal A or B. Once the new resonant frequency of crystal A_s has been established, crystal A_s is substituted for crystal B in Fig. 7. Any crystal may now be made identical to crystal A_s as it was before its resonant frequency was increased (the condition to be duplicated), by substituting such crystal for crystal A in Fig. 7, and adjusting it until its resonant frequency equals f_s and the capacitance ratio

$$\frac{C_1}{C_1'}$$

30 equals 1, as measure according to the procedure described in connection with crystals A and B. It is apparent crystal B_s may serve as a standard to be duplicated by other crystals in similar fashion. The accuracy of measurement of the ratio

$$\frac{C_1}{C_1'}$$

35 resulting from these techniques can be shown to be roughly 100 times greater than could be obtained hitherto, assuming the same accuracy of oscillator frequency indications.

With reference now to Figs. 8 and 9, it will be shown that collaterally the individual values of shunt capacitances C₀, C_{0'}, and series capacitance C₁, C_{1'} of the crystals A and B may also be measured with the circuit of Fig. 7 in accordance with hitherto known procedure. To measure these parameters with respect to crystal A, for example, switches 13 and 14 are placed in their x positions, switches 11 and 12 are placed in their y positions, and switch 29 is opened. It will be recalled that this is substantially the same state of affairs which obtains when the resonant frequency of crystal A is to be measured. However, in this case it is necessary to measure the antiresonant frequency (pole) of the crystal A as well as its resonant frequency (zero), and to this end the frequency of the oscillator is adjusted until the vacuum tube voltmeter indicates a minimum corresponding to the frequency f_b of Fig. 8. Next the switch 29 is closed and capacitor 27 adjusted to a predetermined value which will be denoted C_t. The effect of the capacitor 27 across the crystal is to decrease its antiresonant frequency to a new value corresponding to the frequency f_c of Fig. 1. If S_a is defined as the frequency difference between f_a and f_b , and S_c is defined as the frequency difference between f_a and f_c (as shown in Figs. 8 and 9), it can be shown that,

$$70 C_0 = \frac{C_t}{\frac{S_a}{S_c} - 1} \quad (10)$$

$$C_1 = \frac{2S_a}{f_a} C_0$$

tance C_1 may be easily calculated. The shunt capacitance C_0' of crystal B may be determined in similar fashion by reversing the positions of switches 11 and 12 with respect to switches 13 and 14.

Although the method of measurement according to the present invention has been described in connection with an illustrative circuit which is collaterally adapted to measure resonant frequency and shunt capacitance, it is apparent that the circuit may be simplified considerably if it is to be used only for measuring series capacitance ratio. Various modifications of this nature which remain within the spirit and scope of the invention will no doubt occur to those skilled in the art.

Therefore, what is claimed is:

In a method of manufacturing a crystal filter with predetermined transmission characteristics, including at least a first piezoelectric element of known resonant frequency and a second piezoelectric element of known resonant frequency different from the resonant frequency of said first element and having its series capacitance related to that of said first element in a predetermined ratio, the steps of forming with each of said elements a test network having the transmission characteristics of a

5 symmetrical lattice network, said transmission characteristics differing from those of said filter, measuring the frequencies of maximum attenuation of the network for relation with the resonant frequencies to determine the series capacitance ratio between said elements, adjusting the series capacitance of at least one of said elements to obtain said predetermined ratio, and forming with said elements said filter with said predetermined characteristics.
